UNITED STATES PATENT OFFICE.

HARRY KONERMAN, OF CINCINNATI, OHIO, ASSIGNOR TO THE GLOBE AUTOGRAPHIC REGISTER COMPANY, OF CINCINNATI, OHIO, A CORPORATION OF OHIO.

MEASURED-DELIVERY AUTOGRAPHIC REGISTER.

1,176,223.

Specification of Letters Patent. Patented Mar. 21, 1916.

Application filed January 17, 1916. Serial No. 72,408.

To all whom it may concern:

Be it known that I, HARRY KONERMAN, a citizen of the United States of America, and resident of Cincinnati, county of Hamilton, State of Ohio, have invented certain new and useful Improvements in Measured-Delivery Autographic Registers, of which the following is a specification.

This invention relates to improvements 10 in autographic registers and particularly to autographic registers of the measured delivery manifolding type in which means such as disclosed in United States Letters Patent 1166996, granted to me on January 15 4, 1916, are employed for alining the record sheets thereof. In registers of this type the sheets are drawn from between the interleaved carbon sheets by means of a sliding carriage, to the end of the travel of 20 the carriage. Each record sheet has printed upon it a tabulated form and hence it is desirable that the form upon each sheet shall register with that upon adjacent sheets. Heretofore, in using autographic 25 registers of this type the sheets have become disaligned and out of adjustment to such an extent during the operation of the register, that the corresponding spaces of the printed forms on the several superimposed 30 sheets would not properly register. This disalignment is caused by warpage or buckling of the several sheets as set forth in the specification of the above mentioned patent, and for this reason the stationary 35 alining pins forming the subject matter of the invention disclosed in the above mentioned patent, were provided, apertures being formed in the superimposed sheets for causing the sheets to become properly alined 40 when they were brought into position over the pins.

In the construction above set forth the apertures in the sheets are punched therein a distance apart equal to the spaced distance of the pins, the punch employed in this operation coöperating with two punching dies formed in the same plate. This causes the apertures to always be of the same distance apart, but it sometimes occurs 45 that the sheet web upon which the record forms are printed, several usually being printed abreast of one another to simultaneously produce several record sheet strips, is improperly slitted between the forms so 50 that the apertures are located to one side

or the other of their correct center location. This deviation from their correct position causes the sheets to be improperly centered when they register and to consequently result in the edges of the sheets being turned 60 over by coming into contact with the sides of the way in which they move. This not only results in damaging the sheets, but also in making it impossible to utilize portions of the spaces at the edges of the sheets, especially when these spaces are somewhat narrow. In order to overcome these objections I have devised the mechanism described in the following specification, in which an object is to provide means for 65 adjusting the stationary pins transversely of the register for the purpose of bringing the pins into alinement with the general directrix of the centers of the apertures of the superimposed sheets, so that the pins 70 may operate as efficiently to aline the sheets transversely under such conditions as are presented when the sheet web is slitted improperly as above set forth, as when the pins operate to adjust the sheets longitudinally. This and other objects are attained 75 in the device described in the following specification and illustrated in the drawings in which:

Figure 1 is a fragmental plan view of 80 an autographic manifolding register embodying my invention, parts thereof being broken away for convenience of illustration. Fig. 2 is a fragmental side elevation of an autographic manifolding register embodying my invention, parts being broken 85 away for convenience of illustration. Fig. 3 is a sectional view taken on the line 3—3 of Fig. 1.

The register embodying my invention consists of a frame 4 having a writing table 5 over which the record sheets are drawn, and a reciprocating carriage 6 provided with a clamp 7 adapted to draw the record sheets from the writing table. The carriage 6 is reciprocally mounted on a table 8 provided with guides 9 and 10 on which the carriage travels. Extending from the table 8 over which the record sheets pass when being withdrawn from the machine, are pins 11 and 12, the pins being provided for registering with the apertures 13 of the record sheets 14 as they are drawn into position. Substantially the same mechanism as disclosed in my above mentioned patent is em- 110

ployed for causing the apertures to engage the pins 11 and 12, this mechanism consisting of a plate 15 permanently mounted on rods 16 extending vertically through the table 8 and reciprocally mounted therein. The rods are operated to move vertically to bring the sheets into register with the pins by means of arms 17 and 18 secured to a shaft 19 rotatively mounted in bearings 20 depending from the table. A spring 21 is provided for normally retaining the arms 17 and 18 and consequently the pins 16 and plate 15 in their lifted positions. Secured to the projecting end of the shaft 19 is an externally located arm 22, the end of which is pivotally connected with the swinging lever 27 having its opposite end pivotally mounted on a pin 28 secured in depending lugs 29 of the table 8. A series of inclined lugs 30 are provided on the lever 27 so that as the carriage is brought back to its normal position, a pivotally mounted pawl 31 provided on the carriage 6, will pass over the inclined lugs 30 and cause the lever and consequently the plate 15 to be given a series of rapid upward and downward movements which positively aline the sheets by bringing their apertures over the pins. This mechanism is substantially the same as that described in my above mentioned patent, a series of inclined lugs being provided instead on the one lug disclosed in the patent, for the purpose of giving the sheets several alining movements, should the tendency thereof be to lift from the pins after the first alining movement.

As in the construction disclosed in my above mentioned patent, the sheets are removed from the alining pins by the elevated edge 6^a of the carriage lifting the sheets from the pins upon return of the carriage to its normal position. At the same time a projecting finger 6^b of the carriage engages a finger 40^a of a sheet clamping plate 40 and forces the plate into clamping engagement with the sheets to prevent their displacement after having been removed from the pins. In my improved construction, however, I mount the pins 12 and 13 on a plate 32 located beneath the table 8 and held in sliding engagement therewith by means of screws 33 located in slots 34 formed adjacent to the ends of the plate 32. At one side of the plate a depending lug 35 is formed, the lug being provided with a screw threaded aperture in which an adjustment screw 36 is located, the screw being rotatively mounted in a depending lug 37 formed on the table 8. By means of this adjustment screw 36 the plate bearing the pins may be moved transversely of the table 8 and thus cause the alining pins 12 and 13 secured thereto, to move transversely of the slots 38 formed in the table 8 and the slots 39 formed in the vertically movable alining

plate 15. This is for the purpose of bringing the pins to register with the apertures of the sheets should the sheet web have been slit so that the apertures are located to one side or the other of their correct positions in the sheets.

By this means I am enabled to maintain the advantages attained by the vertically stationary alining pins disclosed in my above mentioned patent, and at the same time provide means for bringing the pins into register with the apertures of the sheets so that the edges of the apertures will not be torn in trying to force the sheets over the pins, as would occur when improper slitting of the sheet web has caused the apertures to have been misplaced therein.

Having thus described my invention, what I claim is:

1. A manifolding autographic register 85 adapted for use with record sheets having a series of apertures, comprising a frame, a table mounted on the frame, a pin vertically stationary with relation to the table and extending above the table, means mounting 90 the pin and adapted to adjust the pin in directions at right angles to its axis, and means adapted to move the sheets to engage the apertures with the pin.

2. In a manifolding autographic register 95 adapted for use with form printed record sheets having a series of apertures, a frame having a sheet supporting table mounted thereon, a pin extending above the table and vertically stationary therewith, means 100 mounting the pin and adapted to adjust it in directions at right angles to its axis, and means adapted to move the sheets to engage the apertures with the pin whereby the forms on the sheets will be alined.

3. In combination in a manifolding autographic register adapted for use with record sheets having a series of apertures, a frame adapted to support the record sheets, a pin vertically stationary with relation to the frame and extending thereabove, means mounting the pin and adapted to adjust it in directions at right angles to its axis, a carriage movably mounted on the frame and adapted to move the record sheets across the pin to bring the apertures in alinement therewith, and a mechanism adapted to engage the apertures with the pin.

4. An autographic register adapted for use with record sheets having a series of apertures, comprising a frame adapted to support the record sheets, a pin extending above the frame and stationary therewith in the direction of its axis, a plate mounting the pin and adjustable with relation to the frame in a substantially horizontal plane, a carriage movably mounted on the frame and adapted to move the record sheets across the pin to bring the apertures in alinement therewith, mechanism adapted to engage 120

the apertures with the pin, and means adapted to remove the sheets from the pin.

5. In an autographic register adapted for use with record sheets having apertures formed therein, the combination of a frame adapted to support the record sheets, a vertically extending pin projecting above the top of the frame and stationary therewith in the direction of its axis, a plate mounting the pin and movable in a horizontal plane, means for adjustably positioning the plate with relation to the frame, a carriage movably mounted on the frame and adapted to move the record sheets across the pin to bring the apertures in alinement therewith, mechanism adapted to engage the apertures with the pin, means adapted to remove the sheets from the pin to permit subsequent delivery of the sheets, and a device adapted 15 to maintain the sheets in alinement after they have been removed by said means from the pin.

6. In combination in a manifolding autographic register adapted for use with record sheets having apertures formed therein, a frame adapted to support the record sheets, a pin extending above the frame and stationary in a direction parallel with its axis, a plate reciprocally mounted on the frame 20 and movable in relation therewith in a direction at right angles to the axis of the pin, an adjustment means operatively connected with the plate, a carriage movably mounted on the frame and adapted to move the record sheets across the pin to bring 25 the apertures in alinement therewith, mechanism adapted to engage the apertures with the pin and operatively connected with the carriage whereby the apertures will be engaged with the pin after the sheets and the pin have been moved into alinement with one another.

7. An autographic register adapted for use with record sheets having apertures formed therein, comprising a frame adapted to support the record sheets, a plate movably mounted on the frame for reciprocation in a substantially horizontal plane, a pin secured to the plate and extending above the frame, a carriage movably mounted on the frame and adapted to move the record sheets across the pin to bring the apertures in register therewith, mechanism adapted to engage the apertures with the pin and 55 operatively connected with the carriage to engage the sheets with the pin after the

apertures have been brought into register therewith, means adapted to remove the sheets from the pin when the carriage is returned to its normal position, and a device 60 adapted to maintain the sheets in their alined positions after removal thereof from the pin.

8. In an autographic register adapted for use with record sheets having apertures 65 formed therein, the combination of a frame adapted to support the record sheets, a plate reciprocally mounted on the frame for movement in a substantially horizontal plane, a pin mounted on the plate with its 70 axis extending in a direction substantially vertical therewith, means for adjusting the position of the plate with relation to the frame, mechanism adapted to engage the apertures with the pin and operatively connected 75 with the carriage to engage the sheets with the pin after the apertures have been brought into register therewith, means adapted to remove the sheets from the pin when the carriage is returned to its normal 80 position, and a device adapted to maintain the sheets in their alined positions after removal thereof from the pin.

9. In combination in an autographic register adapted for use with record sheets 85 having apertures formed therein, a frame adapted to support the record sheets, a plate movably mounted on the frame to reciprocate in a direction substantially horizontal thereto, a pin mounted on the plate with its 90 axis extending substantially vertical therewith, means for adjusting the plate with relation to the frame, a carriage movably mounted on the frame and adapted to move the record sheets across the pin to bring 95 the apertures into registration therewith, mechanism adapted to engage the apertures with the pin and operatively connected with the carriage, means adapted to remove the sheets from the pin during the return of 100 the carriage to its normal position, and a device for maintaining the sheets in their alined positions and adapted to be operated by the carriage previous to the removal of the sheets from the pin.

In testimony whereof, I have hereunto subscribed my name this 14th day of January, 1916.

HARRY KONERMAN.
